UNITED STATES PATENT OFFICE.

EDWARD AL. SMITH, OF FOWLER, COLORADO, ASSIGNOR TO F. W. NASH
AND E. M. SPRAGUE, OF DENVER, COLORADO.

PICK.

SPECIFICATION forming part of Letters Patent No. 698,147, dated April 22, 1902.

Application filed August 16, 1900. Serial No. 27,093. (No model.)

To all whom it may concern:

Be it known that I, EDWARD AL. SMITH, a citizen of the United States, residing at Fowler, in the county of Otero and State of Colorado, have invented certain new and useful Improvements in Picks; and I do declare the following to be a full, clear, and exact description of the invention, such as will enable others skilled in the art to which it appertains to make and use the same.

The invention relates to picks, and more particularly to picks designed for use by miners.

The object of the invention is to provide a pick which shall be of such construction as to permit of its points being removed from the handle when they become worn in order to replace them with new points or when it is desired to change the style of the point for some particular class of work.

A further object is to provide simple, durable, and positive means for locking the points in position; and the final object is to provide a pick of this character which shall be simple of construction, durable in use, and comparatively inexpensive of production.

In the accompanying drawings, Figure 1 is a side elevation of my improved pick, the handle being broken away in order to show the parts on an enlarged scale. Fig. 2 is a longitudinal vertical sectional view, and Fig. 3 is a detail perspective view of the locking-wedge.

In the drawings, 1 denotes the pick-handle, and 2 the eye of the pick, which is connected to the handle in any well-known or desired manner and is provided with a polygonal, preferably rectangular, opening at its upper end.

3 denotes the pick-points, each of which has at its inner end a shank 4, provided with a transverse groove 5, adapted to take a transverse rib 6, formed on the end wall of the polygonal opening.

When the pick-points with their shanks are inserted in the polygonal opening, having their transverse grooves engaged by the transverse ribs formed on the end walls of said opening, there is left a space between the adjacent sides of the shanks, and into

this space I drive a lock in the shape of a wedge, which forces the shanks outwardly against the end walls of the polygonal opening. It will therefore be impossible for the points to become accidentally disengaged, for until the wedge is removed the transverse grooves in the shanks are interlocked with the transverse ribs of the polygonal opening. The wedge is preferably formed with a lug or extension to facilitate its removal.

From the foregoing description, taken in connection with the accompanying drawings, the construction, operation, and advantages of my invention will be readily understood without requiring an extended explanation. The device is exceedingly useful for the purpose for which it is designed and may be placed upon the market at a comparatively small cost.

Various changes in the form, proportion, and the minor details of construction may be resorted to without departing from the principle or sacrificing any of the advantages of this invention.

In the manufacture of picks having but one point a blank corresponding in size and shape to the shank of another pick-point may be employed. It is also evident that the ribs or projections may, if desired, be formed on the shank parts and the recesses or grooves in the wall of the eye or socket. Furthermore, it must be understood that my improved construction is not limited to picks, since it may be employed to advantage in fastening other tools to their handles, the only requirement being that the tool shall have its shank part properly constructed, and this being the case the shape or function of the operating or protruding portion of the tool or device is immaterial.

Having thus fully described my invention, what is claimed, and desired to be secured by Letters Patent, is—

1. The combination with a pick-eye having a polygonal opening and transverse ribs on the interior end walls of said opening, of pick-points having shanks polygonal in cross-section adapted to said opening and formed with grooves to engage said ribs, and a wedge driven into said opening between said shanks.

and spreading them apart and holding the grooves of the shanks locked to the ribs of the opening, substantially as set forth.

2. The combination of a pick-eye having an opening polygonal in cross-section, pick-points having shanks polygonal in cross-section adapted to enter said opening, the pick-point shanks and the adjacent wall of the eye being respectively provided with coöoperating locking recesses and projections, and a wedge-

shaped locking-key inserted in said opening between said shanks.

In testimony whereof I have hereunto set my hand in presence of two subscribing witnesses.

EDWARD AL. SMITH.
